UNITED STATES PATENT OFFICE.

WILLIAM F. KIESEL, JR., OF ALTOONA, PENNSYLVANIA.

WINDOW-SASH.

No. 878,540.

Specification of Letters Patent.

Patented Feb. 11, 1908.

Application filed April 23, 1907. Serial No. 369,749.

To all whom it may concern:

Be it known that I, WILLIAM F. KIESEL, Jr., a citizen of the United States, residing at Altoona, in the county of Blair and State of Pennsylvania, have invented certain new and useful Improvements in Window-Sashes, of which the following is a specification.

This invention relates to improvements in metal window sashes, and more particularly 10 to sashes for the windows of steel railway cars; my object being to provide a sash of this nature which will be light and stiff in construction, and within which the glass will be fastened with dust proof and weather-tight joints; the sash members being so constructed, where the glass is fastened in place, 15 as to provide for sufficient variation between members to correspond with the variations in the thickness of the glass.

20 I attain my object by constructing the sash in the manner illustrated in the accompanying drawings, in which—

Figure 1 represents an end view and an outside elevation of the sash; Fig. 2, a detail 25 on an enlarged scale, showing one corner of the sash; Figs. 3 and 4, sections on the lines *a—a* and *b—b*, respectively, in Fig. 2; Fig. 5, a detail showing one of the clamping bolts by 30 which the glass is fastened in the sash; and Fig. 6, sectional views showing a modification.

Like numerals designate like parts in the several views.

The sash consists of light metal plates bent, 35 pressed, or drawn into the shapes substantially as illustrated in the drawings. The lower rail of the sash is composed of an inside plate 1, bent along its upper edge on an incline at 2, and having a return bend 3 projecting downward from the upper edge of 40 said incline, thus forming the inside molding and a part of the rabbet. The bottom edge is flanged at 4, said flange being inclined to correspond with the incline of the window 45 sill. The outside plate 5 is provided at 6 with an inturned flange corresponding with the flange 4, said flanges being spaced apart and having a rubber dust guard, or weather 50 strip 7 inserted between them. The two flanges and the weather strip are fastened together by means of countersunk screws inserted through the flange 4, and screwed into the clamping strip 8. The inside and outside plates are thereby fastened securely 55 together at their lower edges with a weather

and dust guard strip projecting from the outer edge thereof. The upper edge of the outside plate is bent inward at right angles at 9, then upward at 10, and again inward at 11, the bend 11, projecting to within a short distance of the return bend 3 on the inside plate, and forming therewith the rabbet to receive the glass. The plates 1 and 5 are thus left free to move toward or away from one another at their upper edges.

A metal clamping strip 12, formed from a light metal plate having its edges bent over with close return bends to provide the necessary stiffness, is applied to the outside plate in the first rabbet formed thereon by the 60 bends 9 and 10, and overlaps the second rabbet to fasten the glass in place. This clamping strip is drawn up into place by means of the bolts 13, positioned at suitable intervals along the rail, said bolts having a square 65 shank and being headed over at 14, to engage the return bend 3; said return bend 1 and the bends 10 and 11 on plate 5 being notched out to receive the bolts and prevent them from turning. The bend 10 is inset a sufficient distance to permit the nuts applied to the bolts 13 to lie inside of the plane of the 70 outside surface of plate 5.

The stiles and top rail have narrower inside and outside plates bent into the same 75 form as that already described, except that they are united along their outward edges by the transverse plates 16, the whole being bent up from one integral plate. The stiles and rails are joined together at the corners by 80 miter joints, and united by light cored out castings 20, riveted thereto by countersunk rivets; so as to present a smooth outside and inside surface. By providing the sash with double rabbets the clamping strips and the 85 nuts by which they are fastened in place are positioned entirely within the plane of the outside surface of the sash, thereby permitting the sash to ride freely in the window frame when the sash is raised. To protect 90 the edges of the glass, I apply thereto rubber strips 15 of U-shaped cross-section, to which the clamping pressure is applied, and which also serve to make the joints between the 95 glass and the sash rabbets perfectly dust proof and weathertight.

It will be noted that, by reason of the play permitted between the outside and inside plates where the rabbets are formed, glass of different thickness may be readily applied to 100 105 110 115 120

the sash, and also that the plates may be sprung more or less closely together where the glass varies in thickness.

Instead of using the bolts 13 between the 5 clamping strip 12 and the return-bend 3, I may employ screws, as shown in Fig. 6, in which case I fold the return-bend back upon itself at 17, to furnish sufficient thickness for the screw threads. I prefer, however, to use 10 the bolts, inasmuch as, after, the nuts are set up, the ends of the bolts may be slightly upset to lock them in place; whereas, with the screws there is no means of locking them, and they are apt to work loose.

15 What I claim as my invention and desire to secure by Letters Patent is—

1. A window sash having stiles and rails composed of continuous outside and inside metal plates spaced apart and joined together 20 along their outward edges, said plates being free to move toward or away from one another at their inward edges and bent to form between them a rabbet open at one side to receive the glass, a clamping strip applied 25 to one of said plates and projecting over the open side of the rabbet, and means for drawing the other plate and said strip toward one another to engage and hold the glass within the rabbet.

30 2. A window sash having stiles and rails composed of outside and inside metal plates spaced apart and joined together along their outward edges, the inside plate having a return-bend formed along its free edge, and the out-

side plate having its free edge bent at right 35 angles toward said return-bend to form a rabbet, a clamping strip applied to the outside plate and projecting over the rabbet, and bolts engaging said return-bend and the clamping strip to draw the two together. 40

3. A window sash having stiles and rails composed of outside and inside metal plates spaced apart and joined together along their outward edges, said plates having their free inward edges bent, the one with a return-bend 45 and the other with a right angle bend to form a rabbet, the plates at intervals along said bends being provided with registering notches, bolts fitted into said notches and headed over on the inside to engage the 50 return-bend, and a clamping strip held in place by said bolts to fasten the glass within the rabbet.

4. A window sash having its lower rail composed of outside and inside metal plates, 55 the inside plate being flanged outwardly along its bottom edge and the outside plate being flanged inwardly along its bottom edge, said flanges being spaced apart to receive a weather strip, and means for fastening 60 said flanges together.

In testimony whereof I have affixed my signature, in presence of two witnesses.

WILLIAM F. KIESEL, JR.
